**CROSS-REFERENCE TO RELATED
APPLICATION**

This patent application claims the benefit of priority from Switzerland Plant Breeders Rights Application No. 22-3522 as filed on May 16, 2022, the contents of which is incorporated herein by reference for all it teaches and discloses.

BACKGROUND OF THE NEW PLANT

The present invention comprises a new and distinct variety of *Pelargonium*, botanically known as *Pelargonium zonale* (L.) L'Her. ex Aiton and hereinafter referred to by the variety name '**KLEPZ22620**'. '**KLEPZ22620**' originated from a controlled cross in August 2016 in Nairobi, Kenya between the female *Pelargonium* variety '**KLEPZ05141**' (U.S. Plant Pat. No. 18,628) and the male *Pelargonium* variety '**KLEPZ17484**' (U.S. Plant Pat. No. 30,335).

Seeds from the controlled cross were obtained. The seeds were sown and plants were grown for evaluation. A single plant was selected in June 2017 and subsequently named '**KLEPZ22620**'. In July 2017 '**KLEPZ22620**' was first vegetatively propagated by vegetative stem cuttings in Stuttgart, Germany. '**KLEPZ22620**' was found to reproduce true to type in successive generations of asexual propagation via stem cuttings in Stuttgart, Germany.

SUMMARY

The following are the most outstanding and distinguishing characteristics of this new variety when grown under normal horticultural practices in Latina, Italy.

2

1. Dark green leaves;
2. Small leaf size;
3. A medium to strong leaf zone; and
4. Red flower color,

DESCRIPTION OF THE PHOTOGRAPH

10 This new *Pelargonium* plant is illustrated by the accompanying photograph which shows an overall view of the plant in a pot. The photograph is of an approximately 14-week-old plant grown indoors in Stuttgart, Germany, in April 2021. The colors shown are as true as can be reasonably obtained by conventional photographic procedures.

DESCRIPTION OF THE NEW VARIETY

15 The following detailed descriptions set forth the distinctive characteristics of '**KLEPZ22620**'. Data was collected on 19-week-old plants in Latina, Italy under greenhouse conditions in April 2023. Color references are to The R.H.S. Colour Chart of The Royal Horticultural Society of London (R.H.S.), 5th edition (2007).
